COMMUNICATION SYSTEM

Walter S. Lemmon, New York, N. Y., assignor to
 International Business Machines Corporation,
 New York, N. Y., a corporation of New York

Application October 27, 1934, Serial No. 750,257

6 Claims. (Cl. 178—52)

This invention relates to communication systems for the transmission and reception of character signals, and more particularly to multiplex telegraphy whereby a plurality of messages are transmitted simultaneously from a station and received simultaneously at another station either by line or radio.

The present invention will be explained in conjunction with a single impulse synchronous system and is particularly adaptable to this type of system, in which the different characters to be transmitted and received are represented by single impulse signals which are definitely allocated during particular timed intervals.

Transmission of a plurality of messages simultaneously from one station to another remote thereto has been accomplished commercially in conjunction with the five unit code printing telegraph systems. It will be shown hereinafter how the principle of the simultaneous transmission of a plurality of messages by the present invention differs from the similar transmission of a plurality of messages by the five unit code systems.

Briefly, in the five unit code systems a given unit of time is divided into five intervals during each of which either positive or negative current may be transmitted to operate selecting and printing mechanisms accordingly.

Let it be assumed for illustrative purposes, solely, that the above said unit of time divided into five equal intervals is equivalent to one-fifteenth of a second. Therefore it is understood that this interval of time, one-fifteenth of a second, is the amount of time necessary to transmit a single character.

As mentioned previously, broadly, the printing telegraph system embodied in the present invention involves the shifting of the character impulse along the axis of a timed scale, the position of the impulse thereon determining the character to be selected. Now let it be assumed, again for illustrative purposes solely, that the operation of the printing telegraph unit requires one-fifteenth of a second. It is obvious that the maximum limit of transmission in this theoretical system is fifteen characters per second. Again assuming that it requires but one-three hundredth of a second to send the character impulse in the single impulse system, it is evident that the difference in time required to transmit the character impulse and the time required for the recording unit to operate to effect transmission or reception of the character impulse is a definite interval of time that remains unused when this

particular type of system is used for simplex operation.

It is therefore proposed, and an object of this invention, to employ this unused definite interval of time for the transmission of other similar character impulses, that is during the approximately one-fifteenth of a second period to transmit from a separate and detached printing unit or units character impulses during this spare period of time, or stated in a different manner, it is an object of the present invention to provide means for the transmission of a plurality of character signals from separate printing telegraph units during the timed interval required for sending one character signal during simplex operation.

It is a further object of this invention to transmit a character impulse from one printing unit while another printing unit is effecting the transmission or reception of another character impulse.

A still further object is the provision for the above mentioned multiplex transmission on the same frequency or with impulses or signals of the same characteristics.

A still further object is to provide for multiplex transmission with a simplified arrangement of the transmitting and receiving equipment and the corresponding circuits.

A still further object is to provide for duplex operation on the same frequency or with impulses or signals of the same characteristics.

Various other objects and advantages of my invention will be obvious from the following particular description of one form of mechanism embodying the invention or from an inspection of the accompanying drawings; and the invention also constitutes certain new and novel features of the construction and combination of parts hereinafter set forth and claimed.

In the drawings:

Fig. 1 shows schematically a system by means of which the invention may be carried out.

Fig. 2 is an illustrative time graph of the character impulses.

Fig. 3 is an illustrative time graph showing relative operative positions of time receiving units in the system.

Fig. 4 shows schematically a system by means of which the invention is applied to duplex operation.

Referring now to the drawings in which similar parts are designated by the same numerals in the several views, it is believed that a clear understanding of the invention will be had therefrom

when considered in conjunction with the following description.

For the sake of clarifying the following description a brief explanation of the operation of the form of printing telegraph system embodied herein will be given first, followed by a disclosure of the principle of operation of the complete multiplex transmitting system and a description of its operation, followed by a description of its application to duplex transmission of messages.

General description

The type of single impulse printing telegraph system embodied in this invention is fully disclosed in the copending application Serial No. 15 710,614 filed February 10, 1934 by W. S. Lemmon, et al. and therefore it will be sufficient to disclose the following brief description of its operation.

Referring now to Fig. 1 the transmitting telegraph units T-1 and T-2 are similar units and likewise receiving units R-1 and R-2 are similar so that a description of the operation of one combination will be adequate. In the figure T-1 represents a printing telegraph unit which may 20 be of any well known type having a series of character pivoted key bars 10 and is adapted to initiate a character impulse when the character key is depressed and released. A separate contact 11 is associated with each individual key bar 25 and connected to contact or segments 12 corresponding to the character represented by each key bar.

Rotary arm 13 driven by any suitable means, preferably a motor as indicated by designation 14, 30 is adapted to engage the contacts 12 in rather rapid succession to initiate the character pulse by completing the individual condenser charging circuit coating with the transmitting commutator 15. An individual condenser 16 is provided 35 for each character key bar 10, and is discharged by depressing the key 10 to engage contact 17 to short circuit the said condenser. Charging of the condenser occurs during a predetermined interval of time when the rotary arm 13 engages 40 the particular character segment 12, and when the corresponding depressed key bar is released to its normal position to engage contact 11 thereby completing the charging circuit mentioned above, so that the drop across resistor 18 activates the 45 connected sending circuit 19 and transmitting apparatus 20, as a result of which an impulse is transmitted at a particular moment during a predetermined timed interval.

The character impulse as initiated by the 50 printer transmitter units in the manner just explained and transmission thereof effected by the wave transmitter either over a radio or line network in the usual manner is received in a well known manner by the wave receiver equipment 55 21. The received impulse is then passed to the receiving commutator or distributor 22 and the printing telegraph receiver unit in a manner fully disclosed in the aforesaid application to record the character corresponding to the character 60 pulse transmitted. It is understood that the rotary arm 23 rotated by suitable means such as a motor indicated at 24 is maintained in synchronism with the rotating arm 13 of the transmitting distributor 15 by methods well known in the art 65 25 and one of which is disclosed in the said mentioned application.

It is understood by those skilled in the art how the synchronous distributors are used and may be applied to this type of system to effect the correct selection of the type bar 25 of unit R-1

which is depressed upon energization of the solenoid 26, and each character solenoid attached to a key bar 27 which in turn is connected to the distributor segments or contacts 28, and therefore needs no further explanation.

Operation

It has been mentioned above that the transmitting unit T-2 and the corresponding receiving unit R-2 operate in the same manner as 10 that described for the units T-1 and R-1 (Fig. 1). It was also mentioned above that the said units require a definite interval of time to effect their respective operations, namely, the initiating of the transmission of the character impulse and 15 recording of the character corresponding to said impulse.

Let it be assumed in a simplex system that the rotary arm 13 is driven by its motor 14 at a speed of 900 R. P. M. or 15 R. P. S. If a timed period of 20 one-fifteenth of a second is required for the printing telegraph unit to function it is obvious that it is possible to send but one character impulse during the single revolution of the rotary arm. Referring to Figure 2(a) this condition is 25 represented graphically to show that the time limit of one-fifteenth of a second must elapse before a subsequent character can be transmitted, as for example, the transmission of the character A two times successively.

It is intended to use this time period required for one unit to operate to effect the transmission of the impulse to a second printing telegraph unit, during which interval as mentioned the printing 35 operation is set up. In the system referred to in the above mentioned application this portion of the cycle is unused and wasted. The condition described above is represented in Figure 2(b) whereby the unused timed period is employed for the transmission of a signal from another and 40 different unit.

To accomplish the transmission of a plurality of character impulses during the same period required for the effecting of transmission of an impulse from a single unit, refer now to Fig. 1, 45 the common transmitting distributor 15 has disposed thereupon a plurality of contacts or segments 12, one segment for every character to be transmitted by the plurality of transmitting telegraph units. In the figure two combinations of 50 transmitting and receiving units are shown to illustrate the principle of operation of the invention, it is obvious, however, that more than two units at each station may be used in a similar manner, depending upon the number of segments 55 or contacts arranged on the common distributors, and therefore the invention is not to be limited to the specific number shown merely for illustrative purposes.

The said segments 12, as shown, for each unit 60 are allocated on half of the distributor 15, transmitting unit T-2 is connected to the distributor and transmitting devices 20 similar to the unit T-1 described above. Likewise at the receiving station additional segments 28 are provided on 65 the distributor 22 for the unit R-2, so that there is one segment for every character to be received by said unit.

It was mentioned hereinbefore that rotary arm 23 driven by motor 24 was operated continuously 70 in synchronism with the transmitting rotary arm 13, so that when a signal is transmitted from unit T-1, the signal transmitted is received by its corresponding receiving unit R-1, similarly, the signal transmitted by unit T-2 is received 75

and recorded by its corresponding unit R-2.

Referring now to Fig. 3, the shaded portions of the diagram indicate the time required by the recording units to effect reception of the character impulses.

When its corresponding transmitting unit sends out the selected character pulse in a manner described above, the receiving unit for example, R-1 requires the timed interval of one-fifteenth of a second to record the character, as indicated in the figure. The character signal position is shown in the definite timed interval and it is evident that during this timed interval the unit can record this one character only. From the Fig. 2 it can be seen that a fraction of the timed interval is but necessary to transmit the signal or impulse by the transmitting distributor 15 and wave transmitter 20 over the network, and that a plurality of such impulses could be transmitted over the network in the selected timed period.

Therefore during the printing time of unit R-1, other impulses from separate units may be transmitted, and as shown in the figure unit R-2 is conditioned to receive a signal during this period. And vice versa during the printing time of R-2, a signal may be set up by its corresponding transmitting unit to be transmitted to unit R-2 to be recorded.

In this manner a portion of the wasted cycle may be used to operate a plurality of separate units during the period other units are functioning.

The above description illustrated the application of the invention to the simultaneous transmission of a plurality of messages in one direction, however, the application is not limited to this single application, since it is feasible for duplex operation, to transmit a plurality of messages in opposite directions simultaneously. Referring now to Fig. 4, the transmitting telegraph units T and recording units R operate in the same manner as described above and need not be repeated here. At the transmitting station a separate transmitting and recording unit are connected to the common distributor unit 30 in the manner described, so that the rotating arm 31 engages the transmitting contacts 12 and receiving contacts 28 in succession to operate the respective units. In a like manner the units R-1 and T-2 at the remote station are connected to the common distributor 32 to be operated when the rotary arm 33 operated in synchronism with arm 31 engages its corresponding segments. For duplex operation over a radio network it is necessary to duplicate the wave transmission equipment at both stations as shown, which is obviously not necessary for ordinary line operation.

Referring again to Fig. 3, during the timed period during which the printing operation is set up for unit R-1, transmitting unit T-2 is in a position to be operated to initiate a selected character impulse to be transmitted in an opposite direction to operate its corresponding unit R-2 at a later stage in the cycle.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only

as indicated by the scope of the following claims.

What is claimed is:

1. In a communication system, a transmitting and a receiving distributor, the operation of each distributor being in timed relation with that of the other, a plurality of transmitting and receiving tele-printing units having individual controlling character key bars, said units associated with the said distributors, means associated with the keybars of each of said transmitting units and its associated distributor or distributors to initiate and transmit character impulses at differential times to represent different characters during a predetermined timed interval, each by a single differentially timed impulse, means associated with the key bars of the said receiving units and its associated distributor or distributors to control each receiving unit so as to record the character signals in accordance with their transmission from the corresponding transmitting units, and means included in the said associated distributors to transmit from each transmitting unit the similar differentially timed impulses to control the corresponding receiving units during the said predetermined timed interval required to initiate a single character impulse.

2. In a communication system, a transmitting and a receiving distributor having disposed thereon a plurality of individual contact segments, the operation of each distributor being in timed relation with that of the other, a plurality of transmitting and receiving tele-printing units, having individual controlling character key bars, the said key bars of the units being associated with the distributor contact segments, means associated with the key bars of each of the said transmitting units and its cooperating distributor to initiate and transmit character impulses at differential times to represent different characters during a predetermined timed interval, each by a single differentially timed impulse, means associated with the key bars of the said receiving units and its cooperating distributor to control each receiving unit so as to record the character signals in accordance with their transmission from the corresponding transmitting units, the said individual contact segments of the transmitting and receiving distributors so arranged that the transmitting units are adapted to transmit the similar differentially timed impulses to control the corresponding receiving units during the said predetermined timed interval required to initiate a single character impulse.

3. In a communication system, a transmitting and a receiving distributor having disposed thereon a plurality of individual contact segments, the operation of each distributor being in timed relation with that of the other, a plurality of transmitting and receiving tele-printing units having individual controlling character key bars, switching means included in the transmitting unit and associated with the corresponding key bars to be operated thereby, electromagnetic controlling means associated with the key bars of the said receiving units, the said key bars and switching means of the transmitting units are associated with the individual contact segments of its cooperating distributor whereby signal impulses corresponding to operations of said key bars are initiated and transmitted at differential timed instances during a predetermined timed interval governed by the operation of the cooperating distributor, and the said electromagnetic controlling means are associated with other individual contact segments of its cooperating distributor where-

by the key bars of the receiving unit are operated in accordance with the signals transmitted by its corresponding transmitting unit, said receiving unit governed by the cooperating distributor, and the said individual contact segments of the transmitting and receiving distributors are so arranged that the transmitting units are adapted to transmit the similar differentially timed impulses to control the corresponding receiving units during the said predetermined timed interval required to initiate a single character impulse signal.

4. In a communication system, a plurality of transmitting and receiving tele-printing units having individual controlling character key bars, selection control means associated with the said key bars of each transmitting unit, to be conditioned and maintain the selection of a particular character, electromagnetic means associated with and adapted to control the key bars of the said receiving units, transmitting and receiving circuit control means, the said selection control means and electromagnetic means of the transmitting and receiving units respectively associated with the said circuit control means, means included in the circuit control means which are associated with the transmitting units for initiating the character impulses at differential times to represent the different characters and in accordance with the selection as controlled by the said selection control means, each character represented by a single differentially timed impulse, additional means included in the circuit control means associated with the receiving units controlling the said electromagnetic means whereby the operation of the receiving units is in accordance with the operation of its corresponding transmitting unit, and the said initiating means included in the circuit control means so adapted as to transmit the similar differentially timed impulses to control the corresponding receiving units during the said predetermined timed interval required to initiate a single character impulse signal.

5. In a communication system, a plurality of transmitting and receiving tele-printing units having individual controlling character key bars, a condenser for each key bar of the transmitting units, each condenser adapted to be conditioned upon the operation of the corresponding key bar to represent the selection of the corresponding character, a transmitting and a receiving dis-

tributor having disposed thereon a plurality of individual contact segments, the operation of each distributor being in timed relation with that of the other, a solenoid for each key bar of the receiving units, said condensers and solenoids of the key bars associated with the individual contact segments of the cooperating distributors, means included in the distributor cooperating with the said units and adapted to engage the contact segments for initiating differentially timed impulses during a predetermined timed interval in accordance with the selected conditioned condensers, each character represented by a single differentially timed impulse, the said last mentioned means engaging the contact segments associated with the said solenoids in the receiving units adapted to control the energization thereof in accordance with the transmission of the character impulses from the corresponding transmitting units, and the said contact segments of the transmitting and receiving distributors are so arranged that the transmitting units are adapted to transmit the similar differentially timed impulses to control the corresponding receiving units during the said predetermined timed interval required to initiate a single character impulse signal.

6. In a communication system comprising N number of transmitting and corresponding receiving tele-printer units having individual controlling character key bars, switching means associated with the key bars of the transmitting units, and solenoids associated with the key bars of the receiving units, a plurality of distributors having N groups of individual character segments, said segments associated with the said switching means and solenoids of the units, the operation of each distributor being in timed relation with that of the other, means to initiate single differentially timed character impulses during a predetermined timed interval upon operation of the corresponding switching means by depression of the character key bars to control the energization of the solenoids of the corresponding receiving unit accordingly, and the said groups of character segments so arranged whereby N number of single character impulse signals may be transmitted during the predetermined timed interval required to initiate one character impulse.

WALTER S. LINDGREN.
